FIREARMS RECOIL PAD

Frank A. Pachmayr, Los Angeles, Calif., assignor to
Mershon Company, a Division of Firearms Accessories,
Inc., Los Angeles, Calif., a corporation of California

Filed Sept. 30, 1963, Ser. No. 76,788

Term of patent 14 years

(Cl. D30—1)

FIG. 1.

FIG. 2.

FIG. 3.

FIG. 4

FIG. 5.

FIG. 1 is a top plan view of a firearms recoil pad, showing my new design;

FIG. 2 is a side view of FIG. 1, the opposite side being the same;

FIG. 3 is a bottom plan view of FIG. 1;

FIG. 4 is a left end elevation of FIG. 2; and

FIG. 5 is a right end elevation of FIG. 2.

The essential features of the design reside in the face portion of the pad shown in solid lines.

I claim:

The ornamental design for a firearms recoil pad, substantially as shown and described.
